MOLD FOR CENTRIFUGAL CASTING

Emil A. Nelson, St. Clair Shores, Mich.

Application October 13, 1939, Serial No. 299,349

1 Claim. (Cl. 22—65)

This invention relates to the centrifugal casting of molten metal and particularly to a mold of new and novel construction for use in connection therewith and constitutes a continuation in part of my application for Letters Patent of the United States for improvements in Centrifugal casting method, filed November 13, 1937 and serially numbered 174,296.

Objects of the invention include the provision of a mold for centrifugally casting hollow articles so constructed and arranged that when the mold is positioned with its axis vertical and is charged with metal it will automatically predetermine its own charge; the provision of a centrifugal casting mold so constructed and arranged as to predetermine its own charge of metal when charged with molten metal while in a stationary position; the provision of a centrifugal casting mold having a cylindrical interior surface and an end wall provided with an inwardly axially extending hollow projection serving as an overflow pipe when the mold is charged with its axis in vertical position and the mold is not rotating; the provision of a centrifugal casting mold comprising a bucket shaped member of refractory characteristics having a standpipe positioned centrally of its bottom whereby to predetermine the liquid contents of the mold when the mold is charged while stationary and with its axis in a vertical position; and the provision of a mold for a centrifugal casting operation of such character as to permit it to be charged with molten metal independently of the centrifugal casting machine and thereafter inserted with its charge of molten metal into the machine, the mold being so constructed and arranged as to predetermine the charge of metal receivable thereby prior to its application to a centrifugal casting machine.

The above being among the objects of the present invention, the same consists in certain novel features of construction and combinations of parts to be hereinafter described with reference to the accompanying drawing, and then claimed, having the above and other objects in view.

In the accompanying drawing which illustrates a suitable embodiment of the present invention and in which like numerals refer to like parts throughout the several different views,

Fig. 1 is a partially broken, partially sectioned side elevational view of a centrifugal casting machine in which a mold constructed in accordance with the present invention is illustrated as being operatively positioned and shown in vertical section;

Fig. 2 is a more or less diagrammatic view illustrating the mold shown in Fig. 1 in side elevation and separate from the centrifugal casting machine, supported by a conveyor in a position to receive a charge of molten metal from a furnace, cupola, or the like;

Fig. 3 is a vertical sectional view taken centrally through my improved mold and illustrating the same with its charge of metal after it has been subjected to a centrifugal casting operation and before the finished cast article has been removed therefrom;

Fig. 4 is a slightly enlarged partially broken, partially sectioned side elevational view of the article which is cast by the mold shown in the preceding views.

As is generally understood in the art it is customary practice in connection with the centrifugal casting of metals and particularly where the article to be cast has a material axial dimension as compared to its diameter, to position the mold with its axis in horizontal position and to provide a machine to support and to rotate the mold while in such position. Particularly where such machines are used in quantity production, in order to conserve metal and to limit the amount of machining required to bring the article to finished condition after casting, it is necessary to carefully predetermine the charge of metal which is to be placed in the mold and to be distributed around the inner walls thereof by centrifugal force during the actual casting operation. In accordance with conventional practices molten metal in a cupola or furnace is tapped into a relatively large ladle, an estimated desired quantity of the metal is then poured into a smaller or pouring ladle, the smaller ladle and its contents are hurriedly weighed and metal is either added or discharged from the pouring ladle until approximately the required amount remains therein, the pouring ladle is then transported to the centrifugal casting machine, and the molten metal is then poured from the pouring ladle through a pouring spout and into the interior of the mold which has previously been set in rotation. Thus in conventional practice the metal has an opportunity to cool while it is in the large ladle, also when it is in the small pouring ladle, and also when it passes through the pouring spout into the mold. Considerable time elapses in conventional practice between the time the metal is actually discharged from the cupola or furnace before it enters the mold and, accordingly, loses a considerable amount of its heat before it is finally in the position to be acted upon by centrifugal force in the mold proper. Particularly the small or pouring ladle and the spout leading to the mold proper are relatively cold and contact with these is responsible for a considerable loss of heat in the molten metal. When the molten metal strikes these cold surfaces, and this is particularly true in case of the pouring spouts, the metal spatters and small globules thereof become chilled and are often carried into the final product in such form. It will be realized that the maintenance to the proper heat of the molten

metal is important in centrifugal casting operations if a final product of a desired high quality and texture of material is to be obtained and, accordingly, any loss of heat because of the above 5 mentioned reasons is a material disadvantage.

In filling the pouring ladles and attempting to weight them to obtain an accurate amount of metal therein, the need for speed in getting the molten metal into the mold is so great that the 10 actual error in the final charge in the mold is often considerable, with the result that an undesirable variation in the thickness of the final product is common and results in a disadvantage in the subsequent machining operation which the 15 article cast must usually undergo. Attempts at more accurately weighing the molten metal to be charged has usually resulted in an excessive heat loss from the molten metal, resulting in the formation of blow holes and the like in the final 20 product more detrimental than the variation in thickness of the same.

The present invention is designed to avoid the above described difficulties in the prior art. The avoidance of excessive heat loss of the molten 25 material is accomplished preferably by filling the centrifugal molds directly from the cupola or furnace although they may be charged directly from a relatively large ladle. In carrying out this feature of the present invention it will be 30 realized that it eliminates at least the heat loss occurring in conventional practices in the pouring ladle and in the pouring spout, the bulk of any heat lost by the molten metal being transferred directly to the mold which is a necessary 35 loss in any case and this, accordingly, aids in conserving the heat in the metal between the time it is actually poured and the time at which it is subjected to centrifugal force.

In accordance with the present invention in 40 order to accurately predetermine the charge of metal in the mold in a quick and accurate manner, the mold is so constructed and arranged as to predetermine the amount of metal which may be charged into it. This is accomplished by so 45 constructing and arranging the mold as to provide it with an overflow means which becomes effective when a predetermined amount of metal has been introduced into the mold. By this means the mold is charged with molten metal 50 until the molten metal begins to be discharged from the overflow at which time the charging is discontinued with the assurance that the amount of metal remaining in the mold accurately coincides with the mass desired therein. 55 In carrying out the last mentioned step it will usually be found desirable to fill the mold when the mold is positioned with its axis in a vertical position and the overflow means in such case will usually take the form of a standpipe positioned axially of the mold with the corresponding end of the mold closed except for the opening through the standpipe.

Where the mold is so constructed and arranged as to be charged when its axis is in a vertical 65 position, due to the fact that it is desirable to effect or at least complete the spinning operation of the mold when the axis of the mold is in a horizontal or approximately horizontal position, it will be found necessary to insert the charged 70 mold in the machine and commence spinning of the same while the axis of the mold is in vertical or approximately vertical position and after the mold has reached a sufficient rate of speed to insure throwing of the molten metal to the radial walls thereof to move the mold so as to bring its

axis into the desired position for completion of the casting operation. While this may obviously be accomplished in a number of different ways, one structure is illustrated in the drawing which may be satisfactorily employed and includes a 5 rotatable spindle for supporting and rotating the mold and a support for rotatably supporting the spindle, the support and spindle together with the mold carried thereby being capable of being moved as a unit from a position in which the 10 mold is positioned with its axis vertical to a position in which the mold is positioned with its axis at a material angle to the vertical, or even to a horizontal position where such is desired. It will be appreciated that positioning of the mold with 15 its axis in a horizontal position makes it easier to remove the mold and the article cast therein from the machine after the material from which the article is made has solidified.

Referring now to Fig. 1, the centrifugal casting 20 machine itself is indicated as being provided with a base 10 which is provided with a pair of spaced apart upstanding arms 12 between the upper ends of which extends a horizontal shaft 14 supported thereby. A hollow generally cylindrical housing 25 member 16 positioned with its axis in offset relation with respect to the axis of the shaft 14 is exteriorly provided with a laterally offset boss portion 18 which embraces the shaft 14 between the arms 12 thereby to provide a pivotal support 30 for the housing 16 upon the shaft 14. When the machine is in loading position the axis of the housing 16 extends vertically but as will be apparent its axis may be positioned horizontally or at any other angle to the vertical, as indicated 35 by dotted lines in Fig. 1, by causing the housing 16 to swing about the shaft 14. As a matter of convenience only, in the following description it will be assumed, unless otherwise specified, in describing the construction of the machine, that 40 reference to direction is intended to mean when the machine is positioned as indicated in full lines in Fig. 1, namely with the axis of the housing 16 vertical.

Rotatably mounted within the housing 16 is a 45 hollow spindle positioned with its axis coincident with the axis of the housing 16 and projecting both above and below the housing 16, its upper end being outwardly flanged as at 20 to form a supporting surface and the lower end 50 thereof having fixed thereto a dual pulley 22. The pulley 22 is connected by a pair of belts 24 with a dual pulley 26 secured to the shaft 28 of an electric motor 30 suitably mounted in fixed 55 relation with respect to the housing 16 and movable bodily therewith about the axis of the shaft 14. Seated upon the upper marginal face of the flange 20 are a plurality of spacer blocks 32 arranged in equally angularly spaced relation around the circumference of the flange 20 and 60 these spacer blocks 32 receive upon them a disc-like member 34 which in turn receives and supports the flanged end of the rigid mold support 36. Bolts 38 extend through the flange of the mold support 36, the disc 34, spacers 32 and 65 flange 20 of the spindle and secure all of these parts rigidly together in assembled relation.

The position of the housing 16 and associated parts about the axis of the shaft 14 is controlled by means of a pair of air cylinders 40, one positioned on each side of the housing 16 and each pivotally connected to the base 10 at its lower end by means of a pin 42. Within the cylinder 40 is a conventional piston (not shown) having a connecting rod 44 projecting upwardly through the 75

upper end thereof and pivotally connected as at 46 to the upper portion of the housing 16 eccentrically to the axis of the shaft 14. Suitable connections 48 adjacent the upper and lower ends of the cylinder 40 are provided for the admission and exhaust of fluid under pressure to control the position of the piston in the cylinder 40 and consequently the rotatable position of the housing 16 about the axis of the shaft 14. An air 10 hose 50 is connected by means of a conduit 52 and slip connection 54 with a tube 56 positioned centrally of the housing and the spindle rotatable therein for feeding the air to a mold ejecting device 58 positioned centrally of the disc 34. For 15 a fuller description of the centrifugal casting machine per se and a more detailed description of the manner of operation, reference may be had to the parent application above identified of which the present application is a continuation in 20 part.

Referring now to the mold proper which forms the subject-matter of the present invention and which is shown in Figs. 1, 2 and 3, it will be understood that the actual construction of the mold, 25 that is whether it is made up of an assembly of a plurality of separately formed parts or is made up as an integral structure is of no moment as far as the present invention is concerned. In most cases it will be made up as a baked sand 30 product although in some cases it may be desirable to form it of metallic sections provided with a suitable lining of heat insulating material such as is commonly employed in connection with so-called permanent molds. It will also be appreciated 35 that the interior configuration of the mold will vary in accordance with the article to be formed. As a matter of illustration only in the present instance it is assumed that the mold is intended to form cylinder liners for internal combustion or other engines and which liners take the form of a hollow cylinder having a radially outwardly projecting flange at one end only thereof and as specifically illustrated at 60 in Fig. 4. For the purpose of forming a cylinder liner 60 it is assumed for the purpose of illustration here that the mold which is indicated generally at 62 is formed in two parts from baked sand, namely an upper part 64 and a lower part 66, the upper part being approximately cylindrical and being provided with the usual flange 68 at its open end for predetermining the length in this direction of the article being cast. The lower portion 66 comprises a disc-like portion sealed to the corresponding axial face of the 50 portion 64 and centrally provided with an upwardly projecting boss-like portion or projection 70 provided with a central opening 72 therethrough and which opening is on the axis of the mold. A metal disc or plate 74 underlies the lower face of the portion 66 and is provided with a central aperture aligned with the opening 72. A metallic ring or annular plate 76 overlies the upper face of the portion 64 and threaded rods 78 extend through the mold and cooperate between the plates 74 and 76 to maintain the two portions 64 and 66 in properly assembled relationship. Eyes 80 on the upper ends of the rods 78 provide means by which the mold 62 and its charge of molten metal, here indicated at 82, may be easily transported. It may also be noted at 75 this point that the interior walls of the mold support 36 are slightly tapered and the outer walls of the mold 62 are tapered in a complementary manner so as to insure a proper fit between these parts under all circumstances when assembled

together. As will be noted from an inspection of Fig. 1, when the mold 62 is properly assembled in the mold support 36, the disc 74 overlying the lower end of the mold 62 is preferably positioned a slight distance above the upper face of the disc 34 and member 58.

It is possible to employ a mold of the type shown and described and to insert it in the support 36 while the apparatus is positioned as indicated in full lines in Fig. 1, charging the mold 10 while in such position, and then after initiation of the spinning operation, swing the housing 16 with the mold 62 downwardly to either of the two positions indicated in dotted lines for completion of the spinning operation. In such case advantage 15 may be taken of the particular characteristics of the mold 62 shown except that in such case provisions must be made for eliminating any overflow of the molten metal charge which may pass down the opening 72 from the machine and 20 which provisions are not necessary when the preferred method of employment is used.

In the preferred method of employing the mold shown and described, particularly when used in connection with a centrifugal casting machine of 25 the general characteristic shown and described, is charged with molten metal before it is placed in the mold support 36. Because of this it will be realized that the mold 62 must be self-sustaining under a charge of molten metal therein when 30 stationary and it will be readily recognized that the construction of the mold 62 as previously described in detail is such as to effect this result. Accordingly, in accordance with the preferred method of procedure, a mold 62 is suspended 35 through suitable engagement with the eyes 80 and the rod 78 from a suitable traveling-lifting device 120 suspended for movement from a monorail track 122 as illustrated in Fig. 2. The lifting device 120 may be of any suitable type, either actuated by fluid pressure, electricity, or manually, and is shown by way of illustration only as a chain fall. The mono-rail track 122 is preferably 40 extended past the spout 124 of a suitable cupola or furnace such as 126 so that the mold 62 while 45 supported from the mono-rail track 122, and preferably after it has been initially heated by a torch or the like to reduce the heat losses from the metal to it, may be moved below the spout 124 so as to receive a charge of metal therefrom. 50 As previously mentioned, instead of receiving a charge directly from the cupola or furnace, molten metal from such cupola or furnace may be drawn off into a relatively large ladle and the mold 62 charged directly from the ladle with substantially 55 the same results as here outlined except that in such event a greater heat loss will occur in the metal than where it is charged directly from the cupola or furnace. The height of the boss 70 in each mold 62 will, of course, be so 60 constructed and arranged that when a charge of molten metal is introduced into the mold 62 and its level reaches the height of the top of the projection or boss 70, exactly the required amount of metal for the desired finished article will have 65 been introduced into the mold. Accordingly, in charging the mold 62 as illustrated in Fig. 2, a slight excess of metal is introduced into the mold 62, such excess overflowing the top of the boss or projection 70 and being discharged from the 70 mold through the opening 72 therein, thus insuring in every case that exactly the required amount of molten metal remains in the mold 62 and without the necessity of individually weighing each charge of molten metal as in conventional prac- 75

tice. It will be appreciated that this feature materially shortens the pouring operation as compared to conventional practice.

The mold 62 and its molten contents are then moved along the mono-rail track 122 which extends over the top of one or more machines such as illustrated in Fig. 1, and when over the top of such machine the chain fall 120 is operated to lower the mold 62 and its liquid contents into a mold support 36, it being understood, of course, that during this operation the housing 16 is so positioned relative to the axis of the shaft 14 as to bring the axis of the mold 36 into a vertical position. Because of the tapered exterior surface of the mold 62 and the complementary tapered interior surface of the mold support 36, when the mold 62 is lowered into the mold support 36 it will finally come to rest therein in snug engagement with the inner walls thereof. The mold support 36 thus provides a reinforcement for the walls of the mold 62 against the pressure of the molten metal exerted thereagainst during the subsequent centrifugal spinning action.

It will be appreciated from the above description and in following out the preferred procedure of operation, not only does it insure an extremely accurately charged amount of molten metal in each mold, but because of the fact that the metal is charged directly into the mold from the furnace or at least from a relatively large ladle, the heat losses occurring in accordance with conventional practices through charging into a small ladle carrying an individual charge and in passing through a charging spout is entirely eliminated, and, accordingly, that any loss of heat from a charge is to the mold itself which in any event must eventually absorb the heat from the molten metal. Furthermore, because of the fact that the time element consumed between the time the metal is poured from the furnace to the time the mold is inserted in a machine in running position is substantially less than that required in following out conventional practice, the molten metal at the time it is subjected to centrifugal action in the machine is at a relatively higher temperature, consequently more fluid, and results in sounder castings free of such defects as occur in conventional practices from chilled metal.

As soon as the charge in mold 62 as above described is inserted in the mold support 36 and the chain fall 120 released from it, the motor 30 is energized so as to immediately set the mold support 36 and the mold 62 therein in rotation. As soon as the speed of rotation has increased to such an extent as to insure maintaining of the molten charge of metal in the mold 62 in contact with the outer walls thereof, suitable valves (not shown) are operated to introduce air into the cylinders 40 thus causing housing 16 and all parts carried thereby to pivot around the axis of the shaft 14 in a clockwise direction of rotation as viewed in Fig. 1. Preferably sufficient air is admitted into the cylinders 40 to bring the mold support 36 and the mold 62 carried thereby to the position indicated in dotted lines in Fig. 1 and labeled "spin position", short of a true horizontal position. The mold support 36 may, of course, be moved to a wholly horizontal position if desired but it has been found of advantage to move it to the inclined position shown until completion of the spinning operation when the molten metal has solidified.

As soon as the molten metal has solidified additional air may be introduced into the cylinders 40 to move the mold part 36 to a wholly horizontal position as indicated in dotted lines in Fig. 1 and labeled "unload position", and as soon as the apparatus has reached this position the mold and the cast article therein may be withdrawn from the mold support 36. As soon as the mold 62 has been removed from the mold support 36, air may be admitted to the lower ends of the cylinders 40 whereby to cause the apparatus to resume the vertical position indicated in full lines in Fig. 1 and in which position it is again ready to receive another mold 62 and its charge of molten metal for a repetition of the above described operation.

From the above description it will be appreciated that the mold provided in accordance with the present invention provides a means by which the excessive heat losses occurring in conventional centrifugal casting operations and the occurrence of chilled particles of metal therein is largely eliminated, it provides a means whereby the molds of centrifugal molding machines may be quickly and accurately charged with a desired amount of metal for a casting operation, it provides a means whereby the time element occurring between the time the metal is drawn off from the furnace or cupola to the time it is placed in a centrifugal casting machine and operation of the machine begun is materially shortened, further aiding in avoiding heat losses and retaining the desired fluidity of the molten metal, and is of material importance in eliminating the relatively high proportion of scrap now occurring in centrifugal casting operations and particularly where the article being cast is of a relatively thin wall section.

Formal changes may be made in the specific embodiment of the invention described without departing from the spirit or substance of the broad invention, the scope of which is commensurate with the appended claims.

What is claimed is:

A unitary mold of refractory material including an open and a closed end and provided with internal forming walls complementary in part in size, shape and contour to that desired in the finished cast product and adapted to receive and retain a mass of molten metal introduced thereto and distributed over and maintained in contact with the interior forming walls thereof by a centrifugal force until solidified, a radially inwardly directed annular flange at the open end of said mold for preventing escape of molten metal from said open end when rotating, a stand pipe carried by said closed end and projecting axially into said mold therefrom and serving to limit the volume of molten metal in said mold when stationary, and said mold being so constructed and arranged as to be capable per se of holding a sufficient mass of molten metal for a desired casting operation while stationary, said mold being constructed of a non-metallic heat insulating refractory material sufficiently self-sustaining to hold said charge of metal when unsupported but requiring radial support against bursting during a centrifugal casting operation.
